Primary Examiner — Mary Ann Calabrese*(74) Attorney, Agent, or Firm* — Theodore Heske, III(57) **CLAIM**

The ornamental design for a digital display, as shown and described.

DESCRIPTION

FIG. 1 is a perspective view of a digital display showing our new design;

FIG. 2 is a front elevation view thereof;

FIG. 3 is a back elevation view thereof;

FIG. 4 is a left elevation view thereof;

FIG. 5 is a right elevation view thereof;

FIG. 6 is a top plan view thereof;

FIG. 7 is a bottom plan view thereof;

FIG. 8 is a cross sectional view thereof, taken along line 8-8 in FIG. 2;

FIG. 9 is a cross sectional view thereof, taken along line 9-9 in FIG. 2; and,

FIG. 10 is an alternate perspective view showing our digital display.

The broken line showing of the human in FIG. 1 illustrates environment and forms no part of the claimed design. All other broken lines show portions of the digital display that form no part of the claimed design.

1 Claim, 4 Drawing Sheets(56)
